DESIGN FOR A LADY'S WALKING-SKIRT.

SPECIFICATION forming part of Design No. 14,826, dated February 26, 1884.

Application filed January 23, 1884. Term of patent 3½ years.

To all whom it may concern:

Be it known that I, SARAH JANE SHIELS, of the city, county, and State of New York, have invented and produced a new and original Design for a Pattern of a Lady's Walking-Skirt, (numbered 9,050;) and I do hereby declare that the engraved prints accompanying this specification convey to any one accustomed to using paper patterns a clear understanding of how a garment made up by the pattern will appear.

The design shows a walking-skirt displaying a plain panel at each side; a scarf drapery displaying draping-plaits at its ends and crossing the left-side gore and the front gore di-

agonally; another scarf - drapery exhibiting similar plaits and crossing the front gore and right-side gore diagonally; and a deep full back drapery displaying draping-plaits in its front edges, and loopings at its center.

What I claim as my invention, and desire to secure by Letters Patent, is—

The design for a lady's walking-skirt, as shown in the engraved prints accompanying this specification.

SARAH JANE SHIELS.
